SHIELD

Lambert Orth, Milwaukee, Wis.

Application July 22, 1938, Serial No. 220,674

2 Claims. (Cl. 91—65)

This invention relates to a novel painters' or cleaners' shield, by means of which a surface may be painted while an adjacent marginal surface may be protected.

5 An object of the invention is to provide a device of the type which may be extremely economical of manufacture.

Another object of the invention is to provide a device of the type which is so constructed as to 10 accommodate its plane surface to inequalities on the work surface.

Another object of the invention is to provide a shield with a spring tension in the body thereof which will cause it to grip between adjacent surfaces on a plane, enabling it to maintain its position, as between a window and the sash thereof.

15 Other and further objects of the invention will appear as the description proceeds, reference being had to the accompanying drawing, in 20 which:

Fig. 1 is a view in perspective of the device shown as it would be used to protect a window pane while the lower member of the sash is being painted.

25 Fig. 2 is another view in perspective.

Fig. 3 is a view taken on line 3—3 of Fig. 2.

Referring more particularly to the drawing, the numeral 10 refers to the device generally, which in the preferred form has the curved 30 hooked rod handle 11, and the curved blade portion 12.

The blade 12 is beveled on the three edges, 13, 14 and 15, and the corners 16 and 17 may be rounded off. It is important, however, that the 35 corners 18 and 19 be squared to facilitate close work where the surfaces to be treated have sharp corners.

In Fig. 2, the dotted line 20 serves to indicate a level surface, showing that the blade 12 is longitudinally and concavely curved with reference to

the surface on which it is used. The blade 12 is fashioned of knife or other metal having a spring or resilient quality.

Where a sash is slightly spaced from a pane of glass, it will be understood that the blade 12 5 may be inserted therebetween, and the resiliency or tension thereof will hold it in place against gravity.

It will be understood that the device may be used to protect marginal surfaces while cleaning 10 materials or chemicals are used. The beveled edge in combination with the downwardly concave spring tension insures a close pressure against the surface to be painted or cleaned with a maximum of protection for the surface which 15 is being covered.

The hooked handle member 11 is of value for hanging the tool as on a ledge or sill, or on a rung of a ladder.

It will be understood that the device is capable 20 of various modifications in structure and design without departing from the spirit of the invention, within the scope of the appended claims.

I claim:

1. In a device of the class described, a rectangular blade portion, a handle member centrally of the top thereof, the said blade being curved convexly longitudinally with reference to the bottom thereof and having a spring tension against flattening thereof. 25

2. In a device of the class described, a rectangular edgedly beveled blade portion, a handle member centrally of the top thereof, the said blade being curved convexly longitudinally downwardly and having a spring tension to resist flattening thereof when pressure is applied on the handle to force said blade against a surface to be protected. 35

LAMBERT ORTH.
